APPARATUS FOR MAKING CELLULAR
MASSES

Badcliffe Morris Urquhart, Montgomeryville, Pa.

Application June 21, 1940, Serial No. 341,938,
which is a division of application Serial No.
144,885, May 26, 1937. Divided and this ap-
plication January 15, 1943, Serial No. 472,519

3 Claims. (CL 261—76)

My invention relates to apparatus for making cellular masses, such as foam or the like. The present application is a division of my co-pending application Serial No. 341,938, for Apparatus for making cellular masses, filed June 21, 1940, which is in turn a division of my abandoned application Serial No. 144,885, filed May 26, 1937, for Apparatus and method for making cellular masses.

Cellular masses, for various purposes, have been made hitherto by means of chemical reactions, physical changes due to variations in heat and pressure, or by various mechanical methods. Most of these means have variously proven unsatisfactory by reason of expense of equipment, chemicals, or fuel, as well as frequent lack of adaptability of the apparatus to the place of application of the product.

Yet, the need is great for inexpensive means for making cellular substances, particularly at the place of application of said substances for the uses for which they are intended; and in many instances, there is an important need for varying the size and integral constituents of the individual cells. Instances of such needs may be found in the fire extinguishing field, the building and construction industries, liquid storage tank fields, the food industries, and fields involving the simulation or reproduction of desired views such as scenic effects.

One object of my invention therefore is to provide means whereby a cellular mass such as foam may be practically, readily and inexpensively produced in the general region of a fire, for fire extinguishing purposes.

Another object of my invention is to provide means for making cellular substances such as insulation, acoustic walls, ceilings, wall fillers, panels and the like, for use in the building or construction industries.

A further object of my invention is to provide means for satisfactorily and inexpensively producing scenic displays.

With the above and other objects in view, my invention consists in means for making a cellular substance, which comprises emitting a liquid capable of supporting foam, in the presence of a gas, in a manner to increase the surface of said liquid exposed to said gas operatively to entrain the same, and discharging the resultant mass.

My invention also consists in means for producing a cellular mass, which comprises releasing a quantity of gas, in the presence of a confined foam promoting liquid, operatively to increase the pressure of said liquid, and educing a gas into

said liquid to form a cellular mass or foam, and discharging the resultant mass.

My invention also consists in means for manufacturing a foam dried in a manner to retain the cellular structure of the foam in a substantially solid form.

My invention also consists in means for varying the physical properties of the cellular mass by regulating the relative quantities of gas, liquid, or cellular mass forming substance.

More specifically my invention consists of the apparatus for making a cellular substance, which comprises a closed container adapted to hold a foam promoting liquid, a supplementary container adapted to release gas under pressure into said liquid container, an eductor adapted to commingle a gas and said liquid in predetermined proportions in a manner to form a cellular mass, and a discharge conduit adapted to draw off said cellular mass.

My invention further consists of means for producing a substantially solid cellular mass comprising the residual product of a foam comprising liquid, gaseous and cellular-mass forming constituents, with the liquid constituent removed therefrom.

For the purpose of illustrating my invention, I have shown in the accompanying drawing a form of apparatus which has been found in practice to give satisfactory and reliable results, although it is to be understood that the various instrumentalities of which my invention consists can be variously arranged and organized and that my invention is not limited to the precise arrangements and organizations of the instrumentalities as herein shown and described.

Referring to the drawing in which like reference characters indicate like parts:

Figure 1 represents a vertical sectional view of an apparatus for making cellular masses embodying my invention.

Figure 2 represents a vertical sectional view of the apparatus shown in Figure 1, in cellular mass forming operation.

Figure 3 represents a sectional view of an eductor forming part of the apparatus illustrated in Figures 1 and 2.

Figure 4 represents an elevational view of a modified cage construction embodying my invention.

According to my invention, I provide a container 15 having a cylindrical side wall 16, bottom 17, and a removable cap 18 threaded to the container at 19, and comprising a base 20, peripheral side wall 21 and a handle member 22.

Depending from the base 20, is a cage construction 23. This cage construction 23 comprises tubes 24 and 25, secured to the base 20 of the cap 18, and a rod 26 threaded to the base 20. The tubes 24 and 25 and the rod 26 are placed concentrically about the longitudinal axis of the container 15, and are equidistant from each other.

The lower extremities of the tubes 24 and 25, and the rod 26 support an eductor 27 in a manner hereinafter described, the upper surface of said eductor forming a support for a container 28 charged with gas at any pressure above atmospheric pressure. Container 28 is mounted within the cage formed by the tubes 24 and 25 and the rod 26 and is adapted to be guided thereby in a longitudinal fall when the container 15 is inverted. The container 28, has, on the neck 29 thereof, a frangible diaphragm 30, of sufficient strength to seal the compressed gases within the container, but yet of sufficient plasticity or frangibility to enable a pin 31, extending downwardly from the base 20 of the cap 18 and along its longitudinal axis, to puncture the diaphragm 30 and release the compressed gases within the container 28, when the container 15 is inverted causing container 28 to fall into puncturing relation to said pin 31.

The tube 24 has a port 32 in a portion thereof near the top of the container 15, and the lower part of said tube leads into the inlet 33 of the eductor 27. A nozzle 34 is threaded to the inlet 33 so that the liquid emanating from the tube 24 passes through the nozzle into the interior of the eductor 27. A spiral baffle 35 is inserted within nozzle 34, and is of such pitch and relation to the outlet of nozzle 34, as to atomize, disperse, sub-divide, or otherwise increase the surface of the liquid flowing from said nozzle.

A conduit 36 extends downwardly from the educting chamber 37 to a region near the bottom of the container 15. The tube 25 is connected with the discharge outlet of the eductor 27 in a manner to draw off the educed mixture. The upper end of the discharge tube 25 extends through the base 20 of cap 18, and preferably through the side wall 21 thereof. A flexible discharge hose 38 is secured at one end, to the upper extremity 39 of the discharge tube 25, and at the other end, it may have a discharge nozzle 40 with a shut-off valve 41.

In operation, the cap 18 is removed from the container 15, and the rod 26 is removed therefrom. A container 28 charged with compressed gas, such as nitrogen, nitrous-oxide, carbon-dioxide, air, chlorine, or mixtures thereof, or the like, under suitable pressure is then placed within the cage 23 and the rod 26 replaced therein. The container 15 is then charged with a liquid having viscous qualities, and the cap 18 with discharge cage 23 mounted thereon is then replaced in a manner to seal the contents of the container against escape except through the discharge tube 25.

When it is desired to use the apparatus, handle 22 is grasped by the operator and container 15 is inverted. This causes container 28 to fall and to be punctured by pin 31, thereby releasing the compressed gas therein, as illustrated in Figure 2.

The escaping gas bubbles up through the liquid 42 to form a gaseous region 43 thereabove, relatively to exert pressure downwardly upon the liquid 42 and to urge it through the port 32, tube 24, and eductor 27. At the same time, gas is introduced from the gaseous region 43 into the eductor 27 through conduit 36. In practice, the

liquid 42 passes through the nozzle 34 containing the baffle 35 with such force as to be broken up into finely subdivided streams or particles. This operates to entrain large amounts of gas entering through conduit 36 and to convey the resultant mixture through the discharge tube 25 to the discharge nozzle 40. If desired, an additional pressure head may be built up by closing the shut-off valve 41 until the desired back pressure is obtained and then opening the shut-off valve to release the mixture therefrom. It is to be understood that in place of the eductor 27 illustrated, there may be used an ejector, injector, Venturi tube, proportioner, or the like.

15 The liquid having viscous qualities may be any desired liquid which is capable of entraining a gas. Thus, it may be an aqueous solution of a cementitious material, such as glue, albumen, or of a saponaceous material such as tannin, lico-rice, soap, spent sulphite liquor, or the like, or any material such as casein, glucose or the like, or combinations thereof capable of altering, forming or supporting a filmy surface in the production of foam.

20 25 If desired, a freezing point depressant such as calcium chloride, magnesium chloride, sodium chloride or potassium carbonate may be placed in solution with the liquid to prevent the solution from freezing in the container prior to the operation thereof. Moreover, if desired, a corrosion inhibitor such as potassium chromate or potassium acetate may also be placed in solution with the liquid to protect the elements of the apparatus.

30 35 In Figure 9 is shown a modified cage construction wherein a plurality of compressed gas containers 110 and 111 are mounted within a cage 112 having a corresponding plurality of puncturing pins 113 in puncturing relation to the mouths 40 114 and 115 of the containers 110 and 111, respectively. This form of cage is particularly adapted for use with the generator of Figures 1 to 3 which is intended to be inverted when it is desired to place it in operation. In this connection, cage 45 112 may be bodily mounted in cage 23 or the cage 112 may be used in place of cage 23. It will be understood, of course, that when cage 112 replaces cage 23, the conduits 24 and 25 and rod 26 replace the vertical rods of cage 112. An advantage of 50 this form of cage is that lighter containers may be used; and any desired mixture of gases may be provided for, by using any desired combination of gases in the various containers.

55 By my novel invention, it is possible to change the character of the emitted cellular mass by varying the pressure or volume of gas introduced thereto. Thus, for example, but not by way of limitation, a ratio by volume of three parts of gas at average atmospheric pressure and temperature to one of liquid fed into the eductor or proportioner will produce a wet cellular mass having substantially wet and free flowing qualities. This cellular mass is of a specific weight much greater than that of a cellular mass having a larger ratio of gas to liquid used in the generation thereof.

60 70 A cellular mass having a ratio of ten parts of gas to one of liquid introduced into the eductor or proportioner will be of substantially stiff, resilient and very light weight structure, non-free-flowing, but very cohesive. A cellular mass of this ratio tends to cling to almost any solid or liquid surface. It is capable of supporting fairly substantial weight and can be built up into mounds of substantial size for any of various de-

sired uses, such as the building of scenic effects. Such uses include the simulation or reproduction of glaciers, snow scenes, mountains or rock formations, for photographic purposes. Cellular masses having a ratio of seven or eight parts of gas to one of liquid are of substantially dry characteristics yet of sufficient ability to flow to enable them to spread when emitted from the discharge nozzle. Such a cellular mass is particularly adaptable for use for fire extinguishing purposes. Thus, such foam may be poured on burning surfaces, such as volatile liquids, and will spread over such surfaces operatively to suffocate the combustion thereof. Also, such a cellular mass will cling to a burning wall and is capable of forming a blanket thereon to suffocate the combustion thereof.

Furthermore, quick-setting chemicals, such as salts, cement, plaster of Paris, or gypsum derivatives, may be introduced with the cellular mass forming substance to cause the cellular mass discharged from the generator quickly to solidify. Moreover, fire resisting elements such as silicate of soda may also be introduced therewith.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for making a cellular mass comprising a main container adapted to receive a foam forming liquid and having an open top; a cap for closing said open top; an auxiliary container filled with compressed gas and having a frangible portion; means carried by said cap for normally, slidably supporting said auxiliary container in an inoperative position in the liquid in said main container and comprising a cage formed by a proportioner, a liquid supply conduit adapted to discharge liquid into said proportioner and having an inlet opening into said main container to receive said foam forming liquid, a foam discharge conduit and a removable member; a

5 conduit opening into said main container and connected to said proportioner for supplying a gas to said proportioner; means for puncturing the frangible portion of said auxiliary container so as to release said gas within said main container; a handle adapted to be grasped by an operator for inverting said main container to its operative position thereby puncturing said auxiliary container and releasing said gas whereupon said liquid and said gas flow through their respective conduits under the influence of the gas pressure and through said proportioner where they commingle to form a foam which is discharged into said foam discharge conduit; and means for directing the resulting foam to the desired point.

2. The combination defined in claim 1 wherein the puncturing means comprises a pointed formation formed on said cap.

3. Apparatus for making a cellular mass comprising a main container adapted to receive a foam forming liquid; an auxiliary container filled with compressed gas and supported in said main container; foam forming means providing a cage for supporting said auxiliary container and comprising a proportioner for mixing said liquid and gas to form a foam and providing a seat for said auxiliary container, a liquid supply conduit carried by said main container and connected to the inlet end of said proportioner to support said inlet end and having an outlet nozzle adapted to discharge a dispensed stream of said liquid into said proportioner, a foam discharge conduit carried by said main container and connected to the outlet end of said proportioner to support said outlet end, a removable rod connected to said main container and said proportioner to retain said auxiliary container on said seat in slidable relation to said liquid supply conduit, said foam discharge conduit and said rod and a gas supply conduit connected to said proportioner adjacent its outlet end to supply gas to said proportioner so as to commingle said liquid and gas to form a foam; means for puncturing said auxiliary container upon inversion of said main container to release said gas whereby said liquid and said gas are forced through said proportioner by the pressure of said gas to form foam; and means for directing said foam to a desired point of application.
